UNITED STATES PATENT OFFICE.

AVOCA JONES, OF SEATTLE, WASHINGTON.

DESIGN FOR A LOUD-SPEAKER CASING.

Application filed August 30, 1926. Serial No. 18,906. Term of patent 7 years.

To all whom it may concern:

Be it known that I, AVOCA JONES, a citizen of the United States, and resident of the city of Seattle, in the county of King and State of Washington, have invented a certain new, original, and ornamental Design for Loud-Speaker Casing, of which the following is a specification, reference being had to the accompanying drawings, forming a part thereof.

Figure 1 is a perspective view from the

front taken from a point a little to one side of the central line.

Figure 2 shows the loud speaker in rear elevation; and

Figure 3 is a side or edge elevation of the loud speaker.

I claim:

The ornamental design for a loud speaker casing as shown.

AVOCA JONES.
